UNITED STATES PATENT OFFICE.

JOHN W. CALHOUN, OF CHESTER, PENNSYLVANIA.

STOPCOCK.

1,330,459.

Specification of Letters Patent. Patented Feb. 10, 1920.

Application filed January 21, 1919. Serial No. 272,310.

To all whom it may concern:

Be it known that I, JOHN W. CALHOUN, a citizen of the United States, residing at Chester, in the county of Delaware and State 5 of Pennsylvania, have invented new and useful Improvements in Stopcocks, of which the following is a specification.

My present invention relates to stop cocks, and particularly to devices of this 10 character adapted to be used in water service pipes and in other like connections, to cut off the passage of liquid or fluid therethrough.

An object of the invention is to provide 15 a stop cock of the turning plug type which is so constructed that aside from the inlet and outlet passages the only opening in the case is that through which the turning plug is inserted when fitted in place, and to provide 20 a suitable packing to insure against leakage at this point.

A further object resides in arranging a 25 bearing by which the turning plug is held against excessive tightening within the case to thus insure easy working at all times, and in providing for lubrication at this bearing.

Yet another object is to so construct the parts that the casing structure lends itself 30 particularly to embodiment in an angle cock.

With the above and other objects in view which will be apparent from the drawings in conjunction with the specification and claims, this invention includes certain novel features of construction and combinations 35 of parts which will now be set forth.

In the drawings:

Figure 1 is a view partly in section showing the adaptation of my invention in an angle stop cock.

Fig. 2 is a view similar to Fig. 1 showing a modified application.

In the preferred embodiment the case 1 is so formed that the inlet passage 2 and the outlet passage 3 are substantially at right 45 angles, the flow of liquid or fluid being in the direction indicated by the arrows. In this form of the case or body, an inner shell 4 is cored and is reamed to take the turning plug 5, and around the inlet and outlet passages the casing is threaded or otherwise formed for attachment in a position for use. At one side the shell 4 merges into the lines of the body, and at this point the outlet passage 3 communicates with the interior 55 of the shell, while at the opposite side a fluid port 6 is provided within the body and

around the shell in communication with the intake passage 2, an opening 7 being formed through the shell in line with outlet or discharge passage 3 to establish communication 60 to port 6.

At the bottom of the opening within shell 4, a conical bearing pintle 8 is made of sufficient length that turning plug 5 cannot be forced into the opening of the shell to jam or bind against free turning, and the turning plug has a fluid passage 10 therethrough which lines up with outlet passage 3 and opening 7.

The turning plug is reduced at its outer 70 end to form stem 11, with a shoulder 12 at the point of jointure, and the stem is given a polygonal shape at 13, at its outer end, so that the plug may be more readily turned.

The reamed opening within shell 4 is 75 preferably made somewhat tapered and turning plug 5 is given a corresponding shape so that the plug will not bind when seated on bearing pintle 8, and by reason of the fact that the inner end of the plug is 80 contained entirely within the casing or body there is no possibility of leakage at this point even though the turning plug be comparatively free within the shell and sufficiently loose for ready turning. However, as the cored and reamed opening of the shell must be closed after the turning plug is inserted, the casing or body is externally screw threaded around this opening, a packing gland 14 being provided to 90 be turned onto this threaded portion and to compress a gasket 15 of leather or other suitable material with sufficient packing force against stem 11 and the inner wall of shell 4 that a tight joint is formed at this 95 point, the gasket being held between gland 14 and shoulder 12.

By providing the bearing support for the turning plug, as above outlined, this plug is given a floating mounting; however, it is 100 preferable that the bearing be lubricated at pintle 8, and around the lower portion of the turning plug, to accomplish which purpose a duct 16 is formed in the plug extending from bearing 9 to passage 10.

In the embodiment illustrated in Fig. 2, the principle of construction and the purposes to be accomplished are substantially the same as with the disclosure in Fig. 1; however, the case or body 17 is constructed 110 with the inlet and outlet passages 18 and 19 in alinement, and in this instance the shell

is embraced in the main lines of the body. In this form the bearing pintle is of slightly different shape, and duct 16 is dispensed with, the arrangement and construction of the parts being otherwise similar to the showing in Fig. 1.

From the foregoing it will be seen that I have provided a stop cock structure which adapts itself particularly for use in a number of different connections due to its design and ease of operation, and which eliminates the faults found in the usual types of stop cocks. Therefore, while I have herein set forth only certain specific 10 embodiments, and have mentioned limited possible modifications, I desire to have it understood that in practice I do not wish to limit myself to such specific details as herein particularly set forth, but may resort to 15 any practical modifications falling within the scope of the invention as defined in the appended claims.

I claim:

1. A stop cock including with a case having inlet and outlet passages, said case being provided with an opening to receive a turning plug and having a bearing pintle at the bottom of said opening, a turning plug having a passage therethrough mounted in the opening to turn on said bearing pintle, and a duct leading from the

passage of said turning plug to discharge at the bearing of said pintle.

2. A stop cock including with a case formed to provide angularly opening inlet and outlet passages and having a shell therein in line with said passages open at one end and closed at the other reamed to take a turning plug, a turning plug revolvably mounted in said shell having a passage 40 lining up with the inlet and outlet passages, packing members by which the open end of said shell is closed around said turning plug, said shell having a bearing pintle at the closed end thereof and said turning 45 plug being provided with a bearing to fit said pintle, and a duct leading from the passage of said plug to the bearing thereof.

3. A stop cock including with a case formed to provide right angularly opening 50 inlet and outlet passages and having a shell therein reamed to take a turning plug and into which one of said passages opens, said shell being provided with a side opening in line with the passage opening thereinto, and a turning plug mounted in said shell and having a passage lined up with the side opening thereof and the passage of the casing opening thereinto.

In testimony whereof, I affix my signature.

JOHN W. CALHOUN.
